UNITED STATES PATENT OFFICE.

JOHN F. MUMM, OF BROOKLYN, NEW YORK.

ATTACHING RUDDERS TO BOATS.

SPECIFICATION forming part of Letters Patent No. 310,458, dated January 6, 1885.

Application filed August 20, 1884. (No model.)

To all whom it may concern:

Be it known that I, JOHN F. MUMM, of Brooklyn, in the county of Kings and State of New York, have invented certain new and useful Improvements in Attaching Rudders to Boats; and I do hereby declare the following to be a full, clear, and exact description of the invention, such as will enable others skilled in the art to which it appertains to make and use the same.

My invention relates to an improvement in devices for securing rudders to boats, particularly small boats, in which the rudders are usually removed when the boats are not in use, the object of the same being to connect the rudder to the stern-post of the boat in such a manner that the rudder can be easily and quickly placed in position, and will be free to rise and fall without binding or becoming wedged; and with these ends in view my invention consists in the parts and combinations of parts, as will be hereinafter described, and pointed out in the claims.

In the accompanying drawings, Figure 1 is a view in side elevation showing my improved attachment. Fig. 2 is a horizontal sectional view of the same. Fig. 3 is a vertical sectional view of the lower end of the socket and rudder-slide, and Fig. 4 is a detached view 30 in perspective of the slide.

A represents a boat, to the stern-post B of which the metal socket C is secured. This socket, which extends from the keel to near the upper edge of the stern-post, is made of 35 cast metal, and is provided with the inwardly-extending flanges *a*, between which the metallic slide E rests and moves. This socket is removably secured to the stern-post by screws, and is closed at its lower end by the 40 removable block D, which latter forms the limit of downward movement of the rudder-slide. This socket C and block D are further supported by the metallic plate F, rigidly secured to the keel of the boat, and projecting 45 rearwardly and forming a seat for the socket and block. The flanges *a* of the socket C are parallel or approximately parallel with the stern-post of the boat, and sufficient space between these flanges and the body of the socket

is left for the rudder-slide. The rudder-slide 50 E, which is also made of cast metal, is slightly shorter than socket C, and is provided on opposite sides with grooves *c*, in which the flanges *a* of the socket C rest. The grooves *c* are slightly larger than the flanges *a*, to permit the slide to move vertically without binding, and the lower edge of the slide is preferably rounded or reduced in size, to enable the slide to be quickly and easily inserted in the socket. The portion of the slide which rests 60 in front of the flanges is preferably provided with curved sides, and is smaller than the space between the flanges and the front wall of the socket, to enable it to move vertically without binding or becoming wedged when 65 the rudder strikes an obstruction. The rudder-slide is provided with the rearwardly-projecting perforated lugs *d*, to which the rudder H is secured by the straps I and pins.

By the use of the above-described attachment it is simply necessary to introduce the lower end of the rudder-slide into the upper end of the socket, (which is above the water,) and then release the rudder, which settles 75 down to its position. Heretofore in devices of this character the socket has been dovetailed, and the rudder-slide made of similar shape. Such a construction is objectionable, in that, when the outer or rear end of the rudder strikes an obstruction, the rudder-slide, instead of rising with, will be drawn outwardly and wedged between the undercut flanges of the socket. In my device the rudder, instead of becoming wedged under similar circumstances, will be forced upwardly and carried 85 out of danger.

My device is exceedingly simple in construction, is durable and efficient in use, can be applied to any and all boats, and can be 90 manufactured and sold at a small initial cost.

Having fully described my invention, what I claim as new, and desire to secure by Letters Patent is—

1. The combination, with a single elongated 95 socket constructed substantially as described, of the rudder-slide slightly shorter than the socket, and provided with side grooves, in

which the flanges of the socket rest, the perforated lugs rigidly secured to the outer face of the slide, for the attachment of the rudder, and a block closing the lower end of the socket.

5 2. The combination, with the socket secured to the stern of the boat, the block secured within the lower end of the socket, and the plate secured to the keel and forming a seat for the socket and block, of the rudder-slide and rud-

der, all of the above parts constructed substantially as set forth.

In testimony whereof I have signed this specification in the presence of two subscribing witnesses.

JOHN F. MUMM.
